Holding A.-G., Glarus, Switzerland

Application June 22, 1948, Serial No. 34,433
In Switzerland July 14, 1947

6 Claims. (Cl. 250—33.65)

1

This invention relates to directed beam antenna systems for developing a periodically changing radiation pattern, and more particularly to the mechanical construction of such antenna systems.

A method frequently employed in radar for the exact location of a reflecting object is to transmit a radar beam which varies in amplitude according to a club-shaped pattern, and to impart a circular motion to the axis or maximum amplitude line of the beam, whereby the oscillations reflected back from the object are modulated in amplitude according to its position in space.

In the best known devices, the rotation of the radiation pattern is produced by corresponding rotation of a dipole placed eccentrically in the reflector mirror in the neighborhood of the focal point. The point of heaviest radiation of the dipole thereby moves in a circle of which the center is the focal point of the reflector, but the arrangements for the conduction of current to the rotating dipole were not entirely satisfactory. Furthermore, the periodically changing polarization of the emitted beam of rays of course possesses a rotation corresponding to the dipole rotation. In the guiding of flying objects having, for instance, a dipole as the receiving antenna system, this rotation causes an undesirable additional amplitude modulation of the reception energy, since the direction of the receiving field strength changes periodically in relation to the position of the dipole. This additional periodic amplitude modulation causes a deceptive periodically changing error in the indicated position of the flying body which may lead to false course corrections. In radar instruments, likewise, the rotating polarization of the receiving field strength is a drawback since the reflecting object, from its geometric form, has polarization-dependent reflection properties.

There are also devices in which a periodic pattern variation is imposed upon a constantly polarized beam of rays by a periodic reversing of different individual rays of a composite antenna system. The reversing, which is generally done by capacitive methods, presents considerable difficulties, however, and this method and apparatus have not been entirely satisfactory.

Objects of the present invention are to provide directed beam antenna systems which develop a periodically changing radiation pattern without, however, necessitating a rotation of the radiating antenna or a reversal of antenna currents. Objects are to provide directed beam antenna systems including a parabolic reflector, a dipole located in the neighborhood of the focal point of the reflector and supported from the apex of the reflector by a concentric conductor or coaxial line, and mechanism for translating the center of the dipole along a path about the focal point of the reflector without, however, ro-

2

tating the dipole about the axis of the reflector.

These and other objects and the advantages of the invention will be apparent from the following specification when taken with the accompanying drawings in which:

Figs. 1 and 2 are fragmentary sectional views, on planes through the axis of the reflector, of two directed beam antenna systems constituting different embodiments of the invention; and

Figs. 3 and 4 are fragmentary sectional views of alternative concentric conductor constructions for supporting the dipole for translation along a circular or an elliptical path about the focal point of the reflector.

In the drawings, the reference numeral 1 identifies a parabolic metal reflector having an axis of symmetry $y-y$ through the apex X and the focal point Z of the reflector. A concentric conductor comprising an outer cylinder 2 and central rod 3 passes through the apex section of and is rigidly secured to the reflector 1. The concentric conductor extends beyond the focal point Z and supports the sections 4, 5 of a dipole antenna substantially in a plane transverse to the reflector axis and passing through the focal point, the dipole section 4 which is secured to the central conductor 3 extending through an opening 6 in the outer conductor 2. A secondary reflector or rod 7 is secured diametrically across the outer end of the outer conductor 2 in the plane of the dipole 4, 5, and projects radially from the conductor 2 by approximately the same amount as the dipole. A shaft 8 is secured to and projects axially from the end of the outer conductor 2, the shaft being journalled in a ball-bearing 9 mounted eccentrically in a cam disk 10 on the shaft of a motor 11. The axis of the motor shaft coincides with the reflector axis $y-y$, and the motor is supported on a strap or skeleton frame 12 which is secured to the reflector 1. The concentric conductor 2, 3 is resilient and its inner end is firmly anchored to the reflector 1 by a relatively heavy plate 13.

The dipole antenna 4, 5 is not rotated about its electrical center during use of the antenna system, but rotation of cam disk 10 by motor 11 effects a displacement of the electrical center of the dipole along a circular path of radius r about the focal point Z. The polarization of the electromagnetic waves reflected from reflector 1 is not substantially affected but the axis or line of maximum radiation rotates about the apex X of the reflector 1 by a small angle determined by the eccentricity r of the dipole antenna 4, 5 with respect to the reflector axis $y-y$. The period of circular translatory movements depends upon the motor speed, and the mass of the moving antenna system is preferably compensated by counterweighting the cam disk 10, as illustrated, diametrically opposite the axis of the ball bearing 9 for quiet operation and uniform loading of

the bearing. The load on the ball bearing 9 may be materially reduced or compensated by operating the motor 11 at a speed dependent upon the resiliency or natural period of oscillation of the resilient concentric conductor 2, 3. In place of the circular path of displacement of the dipole antenna 4, 5, an elliptical path may be developed by guiding the shaft 8, or the ball bearing 9, in a radial slot in the cam disk 10.

The described arrangement of the motor 11 beyond the focal point Z may affect the radiation pattern, but this action can be eliminated by a construction, as shown in Fig. 2, in which the motor 11 is located at the rear of the reflector 1. The concentric conductor which supports the dipole antenna 4, 5 takes the form of a resilient tube 2' having a reflector disk 7' mounted on its outer end, and a central tubular conductor 3' within which a resilient shaft 14 is journalled. Shaft 14 is rotated by a motor 11 supported from the mounting plate 13 by a sleeve 15, and the outer end of shaft 14 is secured to a stub shaft 16 carrying an eccentric mass or weight 17 and journalled in ball bearings 9' secured to the reflector disk 7'. A coupling loop 18 for energizing the concentric conductor 2', 3' extends through an opening in the motor-mounting sleeve 15 and into the interior of the outer concentric conductor 2'.

Rotation of shaft 14 and the off-center mass 17 develops a circular wobbling travel of the outer end of the coaxial conductors 2', 3' which support the dipole antenna 4, 5, and the speed of motor 11 preferably is so related to the mass and resiliency of the antenna system that mechanical resonance results, thereby reducing the power required for flexing of the conductor to move the dipole center along a circular path having its center on the axis of the reflector.

In place of the resilient conductors of Figs. 1 and 2, the mechanical assembly which permits translation of the center of the dipole assembly may include universal joints 19 and 20, respectively, see Fig. 3, in the outer conductor 2a and inner conductor 3a of the coaxial line supporting the dipole antenna. Alternatively, as shown in Fig. 4, the outer conductor 2b may be provided with circumferential corrugations 2c adjacent the reflector 1 to increase the flexibility of the antenna system. The universal joint or flexible section of the concentric conductor may be located at the rear of the reflector 1 when the latter has a central opening permitting the movement of the concentric conductor.

It will be apparent that there is considerable latitude in the design and construction of directed beam antenna systems embodying the invention, and that various modifications of the described embodiments fall within the spirit and scope of the invention as set forth in the following claims.

I claim:

1. A directed beam antenna system comprising a stationary parabolic reflector having an axis of symmetry, a resilient concentric conductor having a portion extending through the apex of the reflector and coaxial with said axis of symmetry, means rigidly anchoring said portion of the concentric conductor to said reflector, a dipole supported by said concentric conductor substantially in a plane transverse to said axis and passing through the focal point of said reflector, the outer end of the outer member of said concentric conductor projecting beyond said dipole, and means for displacing the maximum

amplitude axis of the radiated beam at constant speed about and at a constant angle with respect to said axis of symmetry of the reflector; said beam displacing means comprising a motor having a shaft coaxial with said axis of symmetry, path defining means secured to the motor shaft and rotatable thereby, and means coupling said outer end of the outer concentric conductor to said path-defining means at a point displaced from the axis of symmetry of said reflector, whereby through the flexing of said resilient concentric conductor the electrical center of said dipole is displaced along a path encircling the focal point of the reflector.

2. A directed beam antenna system as recited in claim 1, wherein said beam-displacing means includes means for displacing the electrical center of the dipole along a circular path having a center substantially at the focal point of the reflector.

3. A directed beam antenna system as recited in claim 1, wherein the outer member of said concentric conductor is provided with circumferential corrugations adjacent the apex of said reflector to increase the flexibility thereof.

4. A directed beam antenna system as recited in claim 1, wherein said motor is located beyond the focal point of said reflector, as viewed from the apex thereof; and said path defining means comprises a cam disk on said motor shaft, and said coupling means comprises means journaling the outer end of said outer concentric conductor member on and eccentrically of said cam disk.

5. A directed beam antenna system as recited in claim 4, wherein said cam disk includes a counterweight portion at the side of the motor shaft opposite said journaling means.

6. A directed beam antenna system as recited in claim 1, wherein said motor is located at the rear of said reflector and its shaft is resilient, the inner concentric conductor is tubular and said motor shaft extends through the same to project beyond said concentric conductor; said path-determining means is an off-center weight secured to the projecting end of said shaft; and said coupling means comprises a bearing for the shaft and rigidly supported by said end of the outer concentric conductor member.
